WORK SUPPORT FOR SEWING MACHINES

Charles W. Mueller, St. Louis, Mo., assignor to
 Lewis Invisible Stitch Machine Company, St.
 Louis, Mo., a corporation of Maine

Application December 31, 1936, Serial No. 118,657

10 Claims. (Cl. 112—260)

This invention relates to new and useful improvements in work supports for sewing machines particularly of the blind stitch type.

In each of my prior patents 2,038,848 and 2,038-
 5 849, issued April 28, 1936, there is illustrated a
 blind stitch machine of the post type which, how-
 ever, is devoid of a work support. In some sewing
 operations on this type of machine, a work
 support is unnecessary, but in other sewing opera-
 tions a work support is necessary.

The principal object of this invention is to pro-
 vide a sewing machine of the post type with a
 work support which may be swung about a ver-
 15 tical axis from an operative position to an in-
 operative position, or vice versa, and to provide
 means for retaining the same in either of its
 positions.

Another object of the invention lies in the
 construction of the work support whereby when
 20 the same is in its operative position, the operator
 will have freedom of movement for her right hand
 in directing the right hand side of the fabric un-
 der the laterally extending frame arm.

With these and other objects in view which
 25 will more fully appear, the nature of the invention
 will be more clearly understood by following the
 description, the appended claims, and the several
 views illustrated in the accompanying drawings.

In the drawings:

30 Figure 1 is a top plan view of a blind stitch sewing machine of the post type showing the application of my invention thereto,

Figure 2 is a front elevation thereof, and
 35 Figure 3 is an enlarged section taken on the line
 3—3 of Figure 1.

Like reference numerals designate correspond-
 ing parts throughout the several figures of the
 drawings.

As shown in the accompanying drawings, the
 40 sewing machine includes a main frame A which
 comprises a standard 5 having a horizontal upper
 arm 6 extending laterally from the upper end
 thereof and terminating in a forwardly extend-
 ing upper arm 7, and a horizontal base arm 8
 45 which extends laterally from and below the base
 of the standard and terminates in a forwardly
 extending base arm 9, the upper arms 6, 7 being
 spaced above and disposed in substantial regis-
 tration with the base arms 8, 9. Preferably the
 50 standard 5 and the upper arm 6 are cast as a single
 unit, the base arms 8, 9 as a single unit, and the
 upper arm 7 as a single unit, the units being
 rigidly although removably connected together by
 screws or other fastening means.

55 Rigidly fixed to the forward or free end of the

upper arm 7, is a horizontal presser foot B, and
 mounted on said arm above the foot is any suit-
 able stitch forming mechanism.

Located directly under the foot B is a post C on
 which certain mechanism is mounted for pre-
 senting the work to the stitch forming mecha-
 nism.

A work support D is mounted on the frame to
 swing about a vertical axis from an operative po-
 sition to an inoperative position or vice versa.

To this end, a bracket arm E is attached by
 screws 10 to the front edge of the base arm 8
 directly in front of the standard 5. This bracket
 is angular in plan view and includes an upwardly
 and forwardly curved attaching arm 11 which
 15 terminates at its forward end in a lateral arm
 12 which projects towards the post C. The free
 end of the arm 12 is provided with a vertical
 bearing 13 for receiving freely a headed pivot pin
 14.

The work support D is normally disposed just
 below the presser foot B, and is centrally provided
 with a slot 15 which extends forwardly from the
 rear edge thereof for embracing the post C and
 for providing a work supporting portion on op-
 20 posite sides of said post. The work support is
 provided with a laterally extending supporting
 arm 16 which is disposed in a horizontal plane
 located considerably below the horizontal plane
 of the work support, and is integrally connected
 25 thereto by an upwardly curved riser or vertical
 arm 17 which is disposed in close proximity to
 the right hand side of the post C. The right hand
 end of the arm 16 is located under the vertical
 bearing 13 and is provided with a vertical bore
 30 18 for receiving the lower end of the pivot pin 14.
 The arm 16 is rigidly connected to the pin 14
 by a set screw 19 and a coil spring 20 is disposed
 around the pin 14 between the bearing 13 and
 the arm 16. The arm 16 is located in the same
 35 general horizontal plane as the base arm 8, and
 preferably the upper face of the arm 16 is dis-
 posed in a horizontal plane located slightly below
 the horizontal plane containing the upper face
 of the base arm 8. The pivot 14 is spaced from
 40 the riser 17 of the work support a distance suffi-
 cient to receive therebetween the hand or arm
 of the operator.

When the work support is in its operative posi-
 tion as shown by the full lines in Figures 1 and
 50 2, it is retained in position by a latch pin 21 which
 is secured to and depends from the work support
 on the left side of the riser 17 by a set screw 22,
 the lower end of the pin engaging in a seat 23
 55 formed in the base arm 9 on the right of the post

C. When the work support is swung to its inoperative position as shown by the dotted lines in Figures 1 and 2, it is retained in said position by a vertically adjustable stop screw 24 which is engaged in a vertical opening 25 formed in a boss 26 on the bracket arm E which is located at a point intermediate the arms 11 and 12 thereof and on the right hand side of the pivot pin 14. The lower end of the stop screw, when the work support is being swung to its inoperative position, is adapted to be engaged by a stop shoulder 27 which projects upwardly from the arm 16, after which the screw is turned to position the lower end thereof in a seat 28 formed in the arm 16 in front of the stop shoulder 27 and thereby lock the work support in said inoperative position.

From the foregoing, it will be seen that when the work support is in its normal or operative position, the supporting arm 16 and riser 17 conjointly form a passage for the hand and arm of the operator which registers with the space under the lateral frame arm 6 and permits the work to be easily handled and directed under the arm 6 by the operator; that when it is desired not to use the work support the latter may be swung readily to its inoperative position and there locked against movement; that by reason of the spring 20 the latch pin 21 may be readily engaged with or disengaged from its seat 23, and that by reason of the slot 15 in the work support, the latter may be positioned in proper cooperative relation with the post C when the same is swung from its inoperative position to its operative position.

It is of course to be understood that the details of structure and arrangement of parts may be variously changed and modified without departing from the spirit and scope of my invention.

I claim:

1. In a sewing machine, the combination with a frame including a standard, an upper arm extending laterally from the upper end thereof, and a base arm extending laterally from the lower end of the standard and terminating below the free end of the upper arm, of a horizontal presser foot attached to the free end of the upper arm, a post supported on the free end of the base arm directly below the presser foot, a single piece work support recessed for normally embracing the post, and means for mounting the work support on the frame for swingable movements about a vertical axis from an operative position in which it embraces the post to an inoperative position completely removed from the post.

2. In a sewing machine, the combination with a frame including a standard, an upper arm extending laterally from the upper end thereof, and a base arm extending laterally from the lower end of the standard and terminating below the free end of the upper arm, of a horizontal presser foot attached to the free end of the upper arm, a post supported on the free end of the base arm directly below the presser foot, a unitary work support recessed for normally embracing the post, means for mounting the work support on the frame for swingable movements about a vertical axis from an operative position in which it embraces the post to an inoperative position completely removed from the post, and separate means for retaining said work support in its operative and inoperative positions respectively.

3. In a sewing machine, the combination with a frame including a standard, an upper arm extending laterally from the upper end of the standard and terminating in a forwardly extending arm, and a base arm extending forwardly from

the lower end of the standard and having its free end terminating below the free end of the forwardly extending upper arm, of a horizontal presser foot supported on the free end of the upper arm, a post supported on the free end of the base arm below the presser foot, a work support normally embracing the post, and means for swingably mounting the work support for movements about a vertical axis located in front of the standard from an operative position to an inoperative position and vice versa.

4. In a sewing machine, the combination with a frame including a standard, an upper arm extending laterally from the upper end of the standard and terminating in a forwardly extending arm, and a base arm extending forwardly from the lower end of the standard and having its free end terminating below the free end of the forwardly extending upper arm, of a horizontal presser foot supported on the free end of the upper arm, a post supported on the free end of the base arm below the presser foot, a work support normally embracing the post, means for swingably mounting the work support for movements about a vertical axis located in front of the standard from an operative position to an inoperative position and vice versa, and separate means for retaining said work support in its operative and inoperative positions respectively.

5. In a sewing machine, the combination with a frame including a standard, an upper arm extending laterally from the upper end of the standard and terminating in a forwardly extending arm, and a base arm extending forwardly from the lower end of the standard and having its free end terminating below the free end of the forwardly extending upper arm, of a horizontal presser foot supported on the free end of the upper arm, a post supported on the free end of the base arm below the presser foot, a work support including a supporting arm and a connecting riser forming a resultant passage for the operator's arm, said passage registering with the space under the laterally extending upper arm.

6. In a sewing machine, the combination with a frame including a standard, an upper arm extending laterally from the upper end of the standard and terminating in a forwardly extending arm, and a base arm extending forwardly from the lower end of the standard and having its free end terminating below the free end of the forwardly extending upper arm, of a horizontal pressure foot supported on the free end of the upper arm, a post supported on the free end of the base arm below the presser foot, a forwardly extending bracket secured to the frame in front of the standard, and a work support normally embracing the post and pivoted on said bracket to swing about a vertical axis from its operative position to an inoperative position, said work support having a slot extending forwardly from its rear edge to receive the post.

7. In a sewing machine, the combination with a frame including a standard, an upper arm extending laterally from the upper end of the standard and terminating in a forwardly extending arm, and a base arm extending forwardly from the lower end of the standard and having its free end terminating below the free end of the forwardly extending upper arm, of a hori-

zontal presser foot supported on the free end of the upper arm, a post supported on the free end of the base arm below the presser foot, a forwardly extending bracket secured to the frame 5 in front of the standard, and a work support normally embracing the post and pivoted on said bracket to swing about a vertical axis from its operative position to an inoperative position, said work support having a slot extending forwardly from its rear edge to receive the post, 10 said work support including a supporting arm and a connecting riser, the riser being normally positioned adjacent the post.

8. In a sewing machine, the combination with 15 a frame including a standard, an upper arm extending laterally from the upper end of the standard and terminating in a forwardly extending arm, and a base arm extending forwardly from the lower end of the standard and having its free end terminating below the free 20 end of the forwardly extending upper arm, of a horizontal presser foot supported on the free end of the upper arm, a post supported on the free end of the base arm below the presser foot, a forwardly extending bracket secured to the frame 25 in front of the standard, a work support normally embracing the post and pivoted on said bracket to swing about a vertical axis from its operative position to an inoperative position, said work support having a slot extending forwardly from its rear edge to receive the post, and separate means for retaining said work support in its operative and inoperative positions respectively.

9. In a sewing machine, the combination with 30 a frame including a standard, an upper arm extending laterally from the upper end of the standard and terminating in a forwardly extending arm, and a base arm extending forwardly from the lower end of the standard and having its free end terminating below the free 35

end of the forwardly extending upper arm, of a horizontal presser foot supported on the free end of the upper arm, a post supported on the free end of the base arm below the presser foot, a forwardly extending bracket secured to the frame 5 in front of the standard, a work support normally embracing the post and pivoted on said bracket to swing about a vertical axis from its operative position to an inoperative position, said work support having a slot extending forwardly 10 from its rear edge to receive the post, said work support including a supporting arm and a connecting riser, the riser being normally positioned adjacent the post, and the supporting arm being disposed in a horizontal plane located substantially in the horizontal plane of the base arm. 15

10. In a sewing machine, the combination with a frame including a standard, an upper arm extending laterally from the upper end of the standard and terminating in a forwardly extending arm, and a base arm extending forwardly from the lower end of the standard and having its free end terminating below the free 20 end of the forwardly extending upper arm, of a horizontal presser foot supported on the free end of the upper arm, a post supported on the free end of the base arm below the presser foot, a forwardly extending bracket secured to the frame 25 in front of the standard, a work support normally embracing the post and pivoted on said bracket to swing about a vertical axis from its operative position to an inoperative position, said work support having a slot extending forwardly from its rear edge to receive the post, means carried by the work support and cooperating with the base arm to retain the work support in its operative position, and means mounted on the bracket and cooperating with the work support to retain the latter in its inoperative position. 30 35

CHARLES W. MUELLER. 40
